(57) **CLAIM**

The ornamental design for a spiral pet treat, as shown and described.

DESCRIPTION

FIG. 1 is a bottom perspective view of a first embodiment of a spiral pet treat according to the new design;

FIG. 2 is a top perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof;

FIG. 8 is a left side elevation view thereof;

FIG. 9 is a bottom perspective view of a second embodiment of a spiral pet treat according to the new design;

FIG. 10 is a top perspective view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a right side elevation view thereof; and,

FIG. 16 is a left side elevation view thereof.

The broken lines shown in the drawings illustrate portions of the spiral pet treat that form no part of the claimed design.
